SNAP ACTING THERMOSTATIC SWITCH

Maurice D. Stahl, North Canton, Ohio, assignor to The Hoover Company, North Canton, Ohio, a corporation of Ohio

Filed Jan. 31, 1962, Ser. No. 170,201

7 Claims. (Cl. 200—67)

The present invention relates to electric irons and more particularly to a snap acting thermostatic switch therefor.

This is a continuation-in-part of my copending application, Serial No. 34,491, filed June 7, 1960, and now abandoned.

Thermostatic switches for electric irons are old and well known but are usually of the "on-off" type in which the contacts are made and broken slowly. Such switches are entirely unsuitable for high voltages because of the excessive arcing at the contacts as they are made and broken.

Snap acting switches are also old and well known but must be positively moved to both their "off" and "on" positions which require special arrangements of thermostats for both opening and closing such switches.

According to the present invention a normally closed snap acting switch is provided which is opened by a thermostat with a snap action when the sole plate reaches a definite temperature and automatically closes also with a snap action when the sole plate temperature is reduced below a definite point.

According to the present invention, the switch is a complete entity before it is assembled to the sole plate but no individual part thereof is a snap acting device in and of itself.

The snap acting movement is produced by first and second active spring like elements so assembled that the switch contacts will always return to closed position with a snap action when the actuating pressure is released and will open with a snap action when pressure is applied in an upward direction by a thermostat or other actuator to the free end portion of the first of said elements.

According to the invention neither of the two active elements is snap acting in and of itself but becomes snap acting only when assembled and held in the proper relationship.

Contrary to the usual snap acting switch in which the actuator must be manually or otherwise actuated to return the switch to its "on" position, the first of the active elements of the present invention is biased or prestressed so as to return the switch to its "on" position with a snap action when the actuating pressure is released.

The first active element is a stamping of spring material generally rectangular in form with closed ends. One end is formed with an opening for attaching it to a fixed support while the other end is formed with a narrow downturned tang, the shoulders at the sides of the tang forming pivots for the second active element as will later appear. A central tongue extends from the fixed end of the stamping and is provided with a downturned backwardly extending hook shaped portion which forms a pivot point for the tongue of the second active element as will appear later. A small stop tongue is stamped downwardly from the central tongue to form a stop for the switch arm as will later appear.

The second active element is also in the form of a rectangular stamping of spring material having closed ends and a central tongue. The closed end from which the tongue extends carries one of the switch contacts while the opposite end is bent upwardly at right angles so that the inner corners of the sides may form pivots for the legs of the first active element. The central tongue is bowed downwardly and its free end forms a pivot with

2

the backwardly turned hook on the free end of the central tongue of the first active element.

One end of the first active element is supported on a post extending upwardly from the sole plate. A fixed contact is supported on the post and extends outwardly therefrom beneath and parallel to the first active element.

A metallic support having a threaded aperture for receiving the temperature adjusting screw of the manual control for the iron is supported on top of the post and extends outwardly over and parallel with the first active element. The lower end of the adjusting screw contacts the central tongue of the first active element, it being noted that movement of that tongue does not affect the position of the remainder of the first active element.

With the first active element and the fixed contact mounted on the post as above described the second active element may be assembled by positioning its contact end between the fixed contact and the stop with the contacts facing each other, positioning the end of the central tongue of the second active element in the hook on the end of the central tongue of the first active element and pushing on the second active element to place the curved central tongue of the second active element under compression until the upturned ends of the sides of the second active element clear the shoulders formed by the legs of the first active element to each side of the tang and then move the end of the second active element upwardly to engage the inside corners of the sides of the second active element with the shoulders of the first active element.

The second active element will then be detachably engaged with the free end of the first active element but the parts will be under stress to hold the second active element in position with the movable contact on its end in contact with the fixed contact mounted on the post, with the stress of the sides of the first active element being biased to hold the contacts in engagement.

The thermostat is positioned to push upwardly on a tang at the free end of the first active element until the line between the contacts and the pivot between the legs of the two active elements passes the pivot between the tongues of the two active elements at which time the free end of the second active element will move upwardly against the stop and open the switch contacts.

When the pressure of the bimetal is released the reverse action will take place due to the downward pressure on the sides of the first active element.

Other objects and advantages of the present invention will become apparent as the description proceeds when taken in connection with the accompanying drawings in which:

FIG. 1 is a side view partly in section of the switch of the invention,

FIG. 2 is a top view of the first active element of the switch of FIG. 1,

FIG. 3 is a sectional view of the first active element taken on line 3—3 of FIG. 2 and looking in the direction of the arrows,

FIG. 4 is a top view of the second active element of the switch of FIG. 1,

FIG. 5 is a sectional view of second active element of the switch of FIG. 1 taken on line 5—5 of FIG. 4 and looking in the direction of the arrows,

FIGS. 6, 7 and 8 show details of two modifications of the pivotal connection between the two active elements of the switch.

Referring particularly to FIGS. 1-5 inclusive the switch is generally indicated by the reference numeral 10, the first active element by the reference numeral 11 and the second active element by the reference numeral 12.

The switch 10 is mounted on the sole plate 13 by means

of a stud 14 extending through a supporting post generally indicated by the reference numeral 15. As shown in FIG. 1 the stud 14 has its lower end threaded into a threaded opening 16 in the sole plate 13.

The post 15 includes a metallic sleeve 17 surrounding the stud 14 and having a flanged lower end 18 having good thermal contact with the upper surface of the sole plate about the opening 16.

Mounted on the sleeve 17 above the flange 18 is a bimetallic element 19 and a heat conductor 20 which conducts heat from the flange 18 outwardly along the length of the bimetal 19 to prevent overshoot when the iron is first energized.

On top of the bimetal 19 and surrounding the sleeve 17 is a disc 21 of ceramic insulating material insulating the bimetal 19 from a metallic strip 22 which extends outwardly over and parallel to the bimetal 19 and carries a fixed contact 23. On top of the strip 22 in the order named is a metallic take-off lug 24, another ceramic disc 25, a second metallic take-off lug 26, the end 27 of element 11, a ceramic disc 28 and a metallic support 29. A sleeve 30 of ceramic material separates the metallic sleeve 17 from the metallic members 22, 24, 26 and 11 so as to electrically insulate those members from the post 17.

The upper end of the sleeve 17 is provided with a swaged over upper flange 31 which along with the flange 18 renders the switch 10 a unitary structure which may be handled independently of the sole plate 13 so that the switch 10 may be calibrated before being attached to the sole plate 13.

The first active element 11 of the switch 10 of the present invention is a rectangular stamping of spring material having closed ends 27 and 31', sides 32, a central tongue 33 and a downturned tab 34 which forms a stop for the contact arm as will later appear.

The closed end 27 of element 11 is provided with an opening 35, the periphery of which surrounds the sleeve 30 when the switch is assembled as shown in FIG. 1. The closed end 31' of element 11 is provided with a tang 36, adapted to be contacted by an insulating button 37 carried by the free end of bimetal 19 as shown in FIG. 1.

The tang 36 is narrower than the main body of element 11 so as to form shoulders 38 which form pivot points for the element 12 as will presently appear. The tang 36 is connected to the outer ends of sides 32 by upwardly inclined spaced apart strips 39 with a space formed between them in which the downturned end 40 of tongue 33 is positioned. The lower ends of strips 39 form the shoulders 38.

The end 40 of tongue 33 is bent inwardly to form a hook 41 which forms a pivot point for the free end of tongue 42 of element 12 as will appear. The tongue 33 of element 11 is also provided with a raised portion 43 which coacts with a ceramic pin 44 positioned in a bore in the lower end of the adjusting screw 45 carried by the support 29.

The active element 12 is also a closed end rectangular body made from light spring steel. It comprises a closed end 46 which carries the movable contact 47, the tongue 42 which is bowed downwardly as shown in FIG. 5, an upwardly bent closed end 48 and sides 49 connecting the closed ends 46 and 48. The convex corners 50 connecting the closed end 48 with the sides 49 form pivot points which cooperate with the shoulders 38 of element 11 when the parts are assembled as will presently appear. The end 51 of tongue 42 forms a pivot with the hook 41 when the parts are assembled.

It is to be noted that neither the element 11 nor the element 12 is snap acting in and of itself but when assembled as shown in FIG. 1 a snap acting switch is formed.

The element 11 forms a permanent part of the post 15 by placing its closed end 27 over the ceramic sleeve 30

with the perimeter of the opening 35 surrounding the sleeve before the flange 31 is peened over. The end 46 of element 12 with the movable contact 47 facing downwardly is then inserted between the fixed contact 23 and the tab 34 and moved backwardly far enough to engage the end 51 of tongue 42 in the hook 41 to form a pivot point 52. The element 12 is then moved to the left as viewed in FIG. 1 to place the tongue 42 in compression until the corners 50 of the closed end 48 can be moved upwardly to engage over the shoulders 38 to form pivot points 53. The element 12 is then released and will be self supporting, the tongue 42 being under compression and the sides 49 under tension.

The sides 32 of element 11 will be under compression and the central leg 33 under tension.

It is to be noted that in the position shown the movable contact 47 will be in contact with the fixed contact 23 and that a slight space is provided between the tab 34 and the upper surface of the closed end 46 of element 12. That comes about by reason of the fact that the sides 32 of the element 11 are biased downwardly or stressed to hold the closed end or tang 36 downwardly unless pressed upwardly by the button 37 on the end of the bimetal 19 and that is true regardless of the setting of the adjusting screw 45 which acts on the central tongue 33 and raises and lowers the hooked end 41 and thus the pivot point 52 to alter the point at which the switch 10 snaps to its "off" position.

Operation

The contacts are normally closed when the iron is cold and the bimetal 19 is down so that the button 37 is free of or just in contact with the tang 36. As the sole plate 13 heats up the bimetal 19 flexes upwardly and the button 37 pushes the tang 36 and pivot points 53 upwardly while the pivot point 52 remains stationary because the tongue 33 is held stationary by contact with the button 44.

Upward movement of the pivot points 53 will slowly continue until the points 53 are slightly above point 52 at which time the end 46 of element 12 will move upwardly against tab 34 with a snap action and separate the movable contact 47 from fixed contact 23 with a snap action.

The sole plate 13 will then begin to cool and the bimetal 19 to flex downwardly to move the button 37 downwardly. The tang 36 will follow because the sides 32 of element 11 are so stressed to move the tang 36 downwardly. That action will continue until the pivot points 53 move past the pivot point 52; at which time the end 46 of element 12 will move downwardly with a snap action and close the contacts 47 and 23 with a snap action.

Thus according to the present invention the contacts are both opened and closed with a snap action and it is not necessary to provide a separate or special arrangement between the thermostat and switch to positively move a snap acting device to or from its overcenter positions, or in prior art switches.

It is to be noted that the circuit through the switch is from connector 26, active element 11, pivots 53, active element 12, contacts 47 and 23, spring arm 22 and connector 24. Thus the pivots 53 are current conducting.

In certain conditions of use, as in steam irons, the pivots 53 may become corroded and thus unsatisfactory.

For such usages the modifications of FIGS. 6, 7 and 8 may be used. Where the parts are the same they have been given the same reference numerals.

In FIG. 8 a jumper or pig tail 60 is connected between the upturned end 48 of element 12 and the tang 36 of element 11 so that current is conducted between the two active elements 11 and 12 independently of the joints 53.

In some usages it may not be convenient or practical to provide a separate jumper or pigtail in which case the two active elements 11 and 12 can be spot welded together to eliminate the pivots 53 and rely on the flexure

of the metal of the elements to provide the equivalent of the pivots.

In that case the arrangement of FIGS. 6 and 7 may be used. The upstanding end 48 of element 12 is merely bent down on top of the tang 36' of element 11 as shown at 36' and 48' and the two spot welded together at 61. Thus the switch arm 12 will be cantilever mounted on the end of element 11, which is substantially the same as a pivot mounting and which eliminates the corrosion problem of the actual pivot joints as disclosed in FIG. 1.

In the claims where the terms "pivotal attaching means," "pivoted joints," "pivotal connection," "pivot points," "pivotal engagement," etc. are used it is intended that those terms will include a construction wherein the elements 11 and 12 are connected in cantilever fashion by being welded together and the flexing of the metal of the elements forms the pivot.

While I have shown and described but three embodiments of my invention it is to be understood that those embodiments are to be taken as illustrative only and not in a limiting sense. I do not wish to be limited to the particular structure shown and described but wish to include all equivalent variations thereof except as limited by the scope of the claims.

I claim:

1. A snap acting switch comprising first and second strip type elongated spring elements lying in substantial spaced parallelism with each other, each of said elements including compression and tension members, means for supporting one end of the first of said elements so that its other end is free to flex transversely, pivotal attaching means for connecting one end of the second of said elements to the free end of the first of said elements, said pivotal attaching means including pivoted joints between the respective compression and tension members of said elements in such manner as to place said compression members under a compressive stress and said tension members under a tension stress, stops positioned on opposite sides of the non-pivoted end of said second element and so related to said pivotal attaching means that the free end of said second element moves back and forth between said stops with a snap action upon back and forth movement of the pivotally connected ends of said elements, one of said stops comprising a fixed contact, and a movable contact carried by the non-pivoted end of said second element for cooperation with said fixed contact.

2. A snap acting switch according to claim 1 in which said pivotal attaching means includes two spaced apart pivot points so arranged that the non-pivoted end of said second element will snap back and forth between said stops as said pivot points pass their point of alignment with said movable contact.

3. A snap acting switch comprising first and second closed end strip type spring elements each having a pair of parallel side pieces and a central tongue extending from the closed end thereof, said elements lying in substantial parallel relationship with each other with the ends of the side pieces of the first element forming a pivotal connection with the ends of the side pieces of the second element and the end of the central tongue of the first element forming a pivotal connection with the end of the tongue of the second element, the pivotal connection between said side pieces being laterally offset from the pivotal connection between said tongues and said elements being under lengthwise stress such that their closed ends tend to move away from each other, a support for the closed end of said first element, a movable contact carried by the closed end of said second element, a fixed contact carried by said support below said movable contact, a stop positioned above the closed end of said second element, the arrangement being such that movement of said pivotal connections past their point of alignment with said movable contact in either direction will snap the free end of said second element back and forth between said stop and

fixed contact to both open and close said contacts with a snap action.

4. A snap acting switch comprising, a support, a first strip type spring element having a closed end fixed to said support and extending outwardly therefrom, said first element including a pair of parallel side pieces and a central tongue extending away from the closed end thereof, a second strip type closed end spring element, including a pair of parallel side pieces and a central tongue extending away from the closed end thereof, said second element being positioned below said first element with its closed end adjacent said support and carrying a movable contact on its lower face, a fixed contact carried by said support below said movable contact, a stop positioned above the closed end of said second element, the outer ends of the side pieces of the first and second elements being in pivotal engagement with each other, the free ends of the tongues of said first and second elements being in pivotal engagement with each other at a point spaced from the pivotal engagement of said side pieces and said elements being under lengthwise stress such that said movable contact is normally held in contact with said fixed contact and movement of the outer ends of said side pieces to move the points of pivotal engagement past their line of alignment with said movable contact in either direction will snap said contacts to open and closed positions.

5. A snap acting switch according to claim 4 including a bimetallic element for moving the outer ends of said side pieces to open said contacts and means acting on the tongue of said first element to vary the position of the point of engagement between said tongues to thus vary the temperature at which said contacts are opened without affecting the ability of the side pieces of said first element to close said contacts when the bimetallic element cools off.

6. A snap acting switch according to claim 4 in which each of said pivotal engagements is in the form of a pressure contact joint between said elements and said second element is supported on the outer end of said first element by the stresses within said elements.

7. A snap acting device comprising, first and second strip type elongate spring stampings slotted lengthwise to provide compression and tension members, a post supporting one end of said first stamping so that its other end is free to flex transversely, means for detachably and pivotally supporting one end of said second stamping on the free end of said first stamping with the other end of said second stamping free to move transversely and positioned laterally of said first stamping adjacent said post and spaced stops positioned on opposite sides of the free end of said second stamping to permit transverse movement thereof, said detachable supporting means including laterally spaced coating abutments between the respective compression and tension members arranged to place said members under compressive and tension stresses so that the free end of said second stamping normally rests against one of said stops and as the free end of said first stamping is flexed transversely one of said abutments moves past the other to cause the free end of said second stamping to snap against the other of said stops with a snap action.
